FLUID OPERATED PUMP

Roy E. Leonard, Alhambra, Calif.

Application June 8, 1936, Serial No. 84,043

7 Claims. (Cl. 103—5)

This invention relates to pumps and more particularly to fluid-operated pumps for pumping wells, such as water wells and oil wells. This invention is an improvement over my fluid-operated pump disclosed in my application, filed July 12, 1935, Serial No. 30,996.

The general object of the invention is to provide a pump of the character stated which is simple in construction, practical and efficient in operation.

Other objects and advantages will appear hereinafter.

The invention is illustrated in the annexed drawings which form a part of this specification and in which,

Fig. 1 is a fragmentary vertical longitudinal section of my pump illustrating one of the pump units.

Fig. 2 is a fragmentary view of my pump, partly in elevation and partly in longitudinal section, illustrating one of the pump units.

Fig. 3 is a view of my pump with intermediate portions thereof broken out, showing a plurality of the pump units in elevation and brought closely together, and showing other parts of the pump in longitudinal section including the fluid-pressure chamber.

Fig. 4 is a horizontal section of one of the pump units, taken on line 4—4 of Fig. 1.

Fig. 5 is a horizontal section of one of the pump units, taken on line 5—5 of Fig. 1.

Fig. 6 is a horizontal section of one of the pump

the upper end of said casing, there being a packing box 10 in said head surrounding said outlet pipe 5. A fluid inlet pipe 11 extends into and is screw seated in said casing head 9.

Each pump unit 1 comprises a stator 12, a rotor 5 13 and a valve 14.

The stator 12 comprises a lower base member 15, a top member 16, a plurality of superimposed spaced annular vane members 17, 18, and 19, and a pair of spacing sleeves 20 and 21. The base member 15 is provided with a plurality of fluid inlets 22 near its upper end, which inlets are spaced around said member in the side wall thereof equidistantly apart. The lower end wall of said base member is formed with a central inlet 23 and a depending internally-threaded coupling 24 communicating with said inlet. In the coupling 24 of each pump unit 1, except the lowermost unit, is screw-seated the upper end of a connecting pipe 2, and in the coupling 24 20 of the lowermost pump unit is screw-seated the upper end of the inlet pipe 3. The base member 15 of each pump unit is formed with an annular internal seat 25 upon which the valve 14 of the unit rests in its lowermost position while 25 uncovering the fluid inlets 22 in said base member.

The top member 16 of each pump unit 1 is formed with a lower wall 26, an annular inner wall 27 and an outer wall 28 which converges upwardly and terminates in an upwardly-extending internally-threaded coupling 29 with which communicates the outlet 30 in said top member 1 with the outlet formed in said top member 1.

ner sleeve 35 and at their outer ends to an outer sleeve 36, said vanes being inclined and curved slightly from their lower edges to their upper edges, as shown in Fig. 2 of the drawings. The 5 inner sleeve 35 of the lowermost vane member 17 extends downwardly from said member to a point near the lower end of the base member 18, and the valve 14 is slidably fitted between the outer side of said sleeve and the inner side of the cylindrical wall of said base member above the seat 10 25 on said wall as illustrated in Fig. 1 of the drawings.

The rotor 13 comprises an elongated tubular journal, turnably fitted within the inner sleeves 15 35 of the stator vane members 17, 18 and 19 and the inner annular wall 27 of the top member 18, a pair of vertically spaced annular vane members 38 and 39 and a helical blade impeller 40 disposed vertically within and secured to said tubular journal. The vane members 38 and 39 comprise respectively a plurality of spaced radial vanes 41, connected at their inner ends to a hub 42, formed on the journal 37, and at their outer ends to an annular sleeve 43 turnably fitted with 20 25 in the spacing sleeves 20 and 21 respectively, said vanes being inclined slightly from their lower edges to their upper edges in a direction opposite to that of the vanes 34 of the stator vane members 17, 18 and 19. The rotor vane member 38 30 is disposed between the stator vane members 17 and 18, while the rotor vane member 39 is disposed between the stator vane members 18 and 19, with the hubs 42 of said rotor vane members resting upon the upper ends of the inner sleeves 35 35 of said stator vane members 17 and 18 respectively, whereby the rotor 13 is supported in operative position within the stator 12, as shown in Fig. 1 of the drawings.

The well casing 7, packer 8 and head 9 form 40 a fluid-pressure chamber 50. A valve pressure chamber 51 is formed in the lower end of the pump unit 1 below the lower end of the impeller 40, rotor journal 37, inner sleeve 35 of the stator vane member 17 and float-valve seat 25 for the 45 purpose hereinafter described.

The operation of my invention is as follows:

My pump is constructed and arranged so that 50 all of the pump units 1 may be submerged in the oil in the well casing 7, assuming the well to be an oil well, below the normal or natural level of the oil, indicated 52 in Fig. 3 of the drawings. With my pump so submerged fluid under pressure, preferably compressed air or natural gas, is introduced from a source of supply through 55 the supply pipe 11 into the upper end of the fluid-pressure chamber 50 within the well casing 7, which fluid fills the space in said chamber between the oil level 52 and the casing head 9, and the pressure of said fluid upon the oil forces the 60 same first through the inlets 22 in the uppermost pump unit 1 and upwardly through said unit between the vanes of its stator member 17, rotor member 20, stator member 18, rotor member 21, stator member 19, through nozzles 31 and 65 outlet 30 of said pump unit, and through the outlet pipe 5, whereupon the rotor 13 of said pump unit is rotated and oil is drawn by the impeller 40 of said rotor upwardly through the pump from the fluid-pressure chamber 50 and 70 out of the well through the outlet pipe 5, which lowers the level of the oil in said chamber 50. When the level of the oil is lowered in said fluid-pressure chamber 50 below the inlets 22 in said uppermost pump unit 1, fluid under pressure, 75 instead of oil, from said chamber 50 passes

through said inlets 22 and upwardly through said unit and the outlet pipe 5, whereupon the rotor 13 of said uppermost unit is rotated with greater velocity by the action of the fluid pressure upon the vane members 17, 20, 18, 21, and 19 successively and the fluid passing over the upper end of the rotor journal 37 aerates or gasifies the oil, which passes out of the rotor journal and outlet pipe 5, and thereby augments the lifting action of the impeller 40 of said uppermost pump unit. 10 As the uppermost pump unit 1 is operated by the fluid, as aforesaid, the pressure of the fluid upon the oil in the chamber 50 forces oil through the inlets 22 of the next lower pump unit 1 and upwardly through said unit, and operates said 15 pump unit in the same manner as said uppermost unit was initially operated by the oil, whereupon oil is lifted by the impeller 40 of said next lower pump unit through the pipe 2, connected to the outlet of said unit and the inlet 20 23 of said uppermost unit, into said uppermost unit and through the rotor journal 37 thereof, and since the inner diameter of said rotor journal is smaller than the inner diameter of said pipe 2, inlet 23, and the passageway through said rotor 25 journal is further restricted by the impeller 40 of the uppermost pump unit, a substantial portion of the oil under pressure entering the lower end of the uppermost unit is diverted into the pressure chamber 51 against the under side of 30 the valve 14 and raises said valve until it closes the inlets 22 of said uppermost pump unit 1, shutting off the fluid from the pressure chamber 50 into said uppermost pump unit, whereupon the rotor 13 of said uppermost unit is no longer 35 rotated by fluid under pressure entering the unit through its inlets 22 from the pressure chamber 50, and the lifting action of the uppermost pump unit ceases, but the oil is then lifted through the pump by the next lower pump unit 1. The 40 pump units below said next lower pump unit are progressively operated to lift the oil there-through, and such lifting operation discontinued as above described, as the level of the oil descends in the pressure chamber 50, until only the lowermost pump unit 1 is operated by the fluid under 45 pressure in said pressure chamber 50, whereupon the inlet valve 4 is raised off its seat, so that oil is pumped by said lowermost pump unit from the bottom of the well, below the packer 8, up 50 through the pump and out through the outlet pipe 5. If the load becomes too great for the lowermost pump unit 1, any one or more of the units above said lowermost unit will automatically be operated by the fluid under pressure 55 from the pressure chamber 50.

I claim:

1. In a fluid-operated pump, a pump unit provided with an inlet in its lower end, an outlet in its upper end, and fluid inlets in its sides near its lower end, said pump unit comprising a vane stator, a vane rotor, a valve normally resting below said fluid inlets, and an impeller for lifting liquid through said unit, said rotor being formed with a tubular journal rotatably mounted 60 in said stator and communicating at its ends respectively with said inlet and said outlet, the space occupied by the vanes of said stator and said rotor communicating with said fluid inlets and at its upper end with said outlet, and the 65 space below said valve communicating with said inlet in the lower end of said pump unit.

2. In a fluid-operated pump, a pump unit provided with an inlet in its lower end, an outlet in its upper end, and fluid inlets in its sides near its 70

lower end, said pump unit comprising a vane stator, a vane rotor, a valve normally resting below said fluid inlets, and a helical blade impeller for lifting liquid through said unit, said rotor being formed with a tubular journal rotatably mounted in said stator and communicating at its ends respectively with said inlet and said outlet, the space occupied by the vanes of said stator and said rotor communicating with said fluid inlets and at its upper end with said outlet, and the space below said valve communicating with said inlet in the lower end of said pump unit.

3. In a fluid-operated pump, a pump unit provided with an inlet in its lower end, an outlet in its upper end, and fluid inlets in its sides near its lower end, said pump unit comprising a vane stator, a vane rotor, a valve normally resting below said fluid inlets, and an impeller for lifting liquid through said unit, said rotor being formed with a tubular journal rotatably mounted in said stator and communicating at its ends respectively with said inlet and said outlet, said unit being provided with a plurality of annularly-spaced ducts leading from the upper end of the space, occupied by the vanes of said stator and said rotor, into said outlet and said space communicating with said fluid inlets, and there being a pressure chamber below said valve communicating with said inlet in said pump unit.

4. In a fluid-operated pump, a pump unit provided with an inlet in its lower end, an outlet in its upper end, and fluid inlets in its sides near its lower end, said pump unit comprising a vane stator, a vane rotor, a valve normally resting below said fluid inlets, and a helical blade impeller for lifting liquid through said unit, said rotor being formed with a tubular journal rotatably mounted in said stator and communicating at its ends respectively with said inlet and said outlet, said unit being provided with a plurality of annularly-spaced ducts leading from the upper end of the space, occupied by the vanes of said stator and said rotor, into said outlet, and said space communicating with said fluid inlets and there

being a pressure chamber below said valve communicating with said inlet in said pump unit.

5. The pump unit as characterized by claim 1, in which the stator is formed with a plurality of spaced vane members and the rotor is formed with a plurality of spaced vane members interposed between the stator vane members.

6. In a fluid-operated pump, a pump unit provided with an inlet in its lower end, an outlet in its upper end and fluid inlets in its sides near its lower end, said pump unit comprising a vane stator, a vane rotor, a valve normally resting below said fluid inlets, and an impeller for lifting liquid through said unit, said rotor being formed with a tubular journal rotatably mounted in said stator and communicating at its ends respectively with said inlet and said outlet, the space occupied by the vanes of said stator and said rotor communicating at its lower end with said fluid inlets and at its upper end with said outlet, said tubular rotor journal being smaller in diameter than the inlet in the lower end of said pump unit, and said valve surrounding said rotor journal, there being a valve-pressure chamber in the lower end of said unit below said valve communicating with said inlet.

7. A fluid-operated pump comprising a fluid pressure chamber closed at its lower end with a packer and at its upper end with a head, a plurality of vertically spaced rotary pump units in said fluid-pressure chamber, pipes connecting said units, an inlet pipe connected to the lowermost unit and leading through said packer into the bottom of a well, an outlet check valve in said inlet pipe, an outlet pipe leading from the uppermost pump unit through said head, a fluid-supply pipe leading into the upper end of said fluid-pressure chamber, said pump units being constructed and arranged to operate successively from the uppermost to the lowermost unit, under the influence of the fluid pressure upon liquid in said fluid-pressure chamber.

ROY E. LEONARD.
